UNITED STATES PATENT OFFICE.

HARRY W. DENHARD, OF SAN FRANCISCO, CALIFORNIA, ASSIGNOR TO THE CUTLER-HAMMER MFG. CO., OF MILWAUKEE, WISCONSIN, A CORPORATION OF WISCONSIN.

ELECTRIC RESISTANCE UNIT.

1,143,576.

Specification of Letters Patent. Patented June 15, 1915.

Application filed October 31, 1911. Serial No. 657,804.

To all whom it may concern:

Be it known that I, HARRY W. DENHARD, a citizen of the United States, residing at San Francisco, in the county of San Francisco and State of California, have invented new and useful Improvements in Electric Resistance Units, of which the following is a full, clear, concise, and exact description, reference being had to the accompanying drawing, forming a part of this specification.

My invention relates to electric resistance units.

It has among its objects to provide an improved resistance unit.

A further object of my invention is to provide an improved electric resistance unit of high heating capacity especially adapted to use in electric heating devices which may be constructed in a very compact form, the heat being evenly distributed to the object to be heated.

Other objects and advantages of my improved construction will hereinafter appear.

25 In the accompanying drawings I have, for purposes of illustration, shown one form which my invention may assume in practice. My invention, however, is not limited to this form, but may assume other forms.

30 Figure 1 shows a top plan view of a unit with the outer protecting sheet removed; Fig. 2 shows a top plan view of the base member for the unit; Fig. 3 shows a sectional view of a unit in position in an iron; Fig. 4 shows a plan view of a section of slotted resistance material; Fig. 5 shows a perspective view of the end of the resistance material after it has been folded as shown in Fig. 1.

40 In these drawings I have for purposes of illustration shown one form which my invention may assume when applied to a heating element for use in an electric iron. As therein illustrated, an insulating base 1 is preferably covered with a resistance material 2, which may be formed in one piece and wound lengthwise around said base in such a manner that a plurality of layers of resistance material are provided on each surface of the base, the layers of resistance material on one side of the base lying opposite and in parallel planes to those on the other side of the base.

45 The insulating base 1 may be formed of any suitable insulating material. In a pre-

fferred form I use mica as this insulating material. The resistance material 2 may assume various forms. In a preferred form, however, I employ slotted resistance ribbon. This resistance ribbon is wound upon the 60 base 1 after the manner of tape, passed up one side of the base and down the other side in a parallel plane, and substantially opposite the first strip until the entire surface of the base is covered as shown in Fig. 65

1. In the construction herein illustrated, the base 1 is made in such a shape that it will conform to the opening in the interior of an electric iron. In order that the resistance material may be suitably wound 70 upon the same and that the strips may be suitably spaced apart, the base is provided with a plurality of steps 3 in its sides which are each adapted to receive a strip of the resistance material 2. In order that the 75 strips of resistance material may be spaced apart from each other, suitable projections 4 are preferably provided in the corners of the steps 3 and a projection 5 is provided at the top of the base. In a preferred form, 80 in order to space the strips at the back of the unit, a plurality of spaced projections 6 is provided across the back of the base as shown in Fig. 2.

85 In a preferred form, the resistance material is made up from a single strip of slotted resistance ribbon of the type shown in Fig. 4, and the end connections for the same are made by bending adjacent convolutions of this strip in the manner shown in 90 Fig. 5. When it is desired to form a unit of the shape shown in Fig. 1, the halves 7 and 8 of a convolution of the slotted resistance ribbon are bent along a line which constitutes a continuation of the slot 9 until these 95 halves 7 and 8 are substantially parallel to each other. The part 7 is then bent backward at right angles or upward as shown in Fig. 4 along a longitudinally extending line 10 and is then again bent along a second 100 longitudinally extending line 11. It is thus seen that, as shown in Fig. 5, the two sections of the resistance material may be arranged in parallel planes and connected by a connecting strip of unslotted resistance 105 material which constitutes the part 7 shown in Fig. 4. By bending the resistance material in this improved manner, I am able to form a unit in which the strips may be brought on the different sides of the base in 110

parallel rows by using a single strip of slotted resistance ribbon. No additional cutting of the resistance material is required and it may be readily shaped so as to provide the desired connections. Thus it is seen that the section 7 forms a connecting strip which may be folded over one of the projections 6 on the base and that the several strips are effectually spaced by these 10 projections. By this improved manner of making up the unit, I am able to provide a continuously wound unit in which the strips may be very compactly arranged so that the heating effect is evenly distributed 15 over the surface of the object to be heated and in which there is little or no space between the strips of resistance material beyond that necessary to properly insulate the same from each other.

20 After the strip of resistance material has been wound or looped upon the base 1, it is preferably placed between sheets of insulation 12 and 13 of a slightly larger size than the base 1 so the unit may be effectually insulated from the interior of the iron. These 25 insulating sheets are preferably, as in the usual construction, compressed upon the resistance material by means of suitable bolts 12, which pass down through the unit and 30 serve to compress the same between the body portion 15 of the iron and the heat retaining or ballast plate 16. In order that the resistance unit may be effectually insulated from these bolts, the perforations 17 in the 35 sheets 12 and 13 through which the bolts are passed are preferably made slightly smaller than the perforations in the base 1. If desired, I may pass these bolts through one or more of the strips of resistance material, 40 punching out a portion of the same as shown in Fig. 1, and leaving a portion of the strip unslotted adjacent the punched out portion as shown in that figure.

In order that there may be no short circuiting due to an accidental contact at the 45 connection points around the projections 6, I may if desired clip the corners of the resistance material as shown at 18 in Fig. 1. Further, in order to provide suitable terminal 50 connections for the unit, I preferably slightly extend the ends of the resistance material as at 19 and leave these portions unslotted. In order that no short circuiting may occur at these ends, I preferably 55 cut away a V-shaped portion 20 as shown in Fig. 1. It is of course evident that the terminals 19 may be connected in any suitable manner to the line. If desired, for instance, suitable terminal connections or 60 plugs may be riveted or otherwise secured in perforations 21 in the ends of the same.

By my improved construction I have provided an electric resistance unit in which the resistance material covers substantially 65 the entire surface of the base and in which

the resistance material may be wound upon both sides of said base, the strips on each side being so closely located with respect to each other as to form a practically continuous sheet of resistance material. By my 70 improved construction, while these strips of resistance material are very compactly arranged, they are, at the same time, effectually insulated from each other and are held securely in position by the base, so that there 75 is no danger of short-circuiting. By my improved construction I am able to use a continuous strip of resistance material of the flat slotted ribbon type and am thus able to obtain an increased heating effect and, at 80 the same time, provide a unit which is exceptionally thin, so that it occupies but little space and the heat may be transmitted directly to the surface to be heated. Further, when the unit is assembled, the parts of the 85 same are securely held in position so that the unit is well adapted to withstand long use in service. Further, by my improved construction I have provided an efficient unit which may be manufactured at small ex- 90 pense.

While I have in this application described one specific form which my invention may assume in practice, I do not wish to be limited to this form, which is shown for 95 purposes of illustration, but wish rather to include within the scope of this application, all those forms of my invention falling within its spirit.

What I claim as new and desire to secure 100 by Letters Patent of the United States is:

1. A resistance unit comprising a base and a continuous uniform strip of slotted resistance ribbon formed into a series of parallel convolutions each extending completely 105 around a portion of said base and each having its sections on opposite sides of said base in the same vertical plane.

2. A resistance unit comprising a base and a continuous uniform strip of slotted 110 resistance ribbon formed into a series of parallel convolutions each extending completely around a portion of said base and each having its sections on opposite sides of said base in the same vertical plane, said 115 base having portions for maintaining adjacent convolutions of said resistance ribbon in a spaced relation.

3. A resistance unit comprising a base and a continuous uniform strip of slotted resistance ribbon formed into a series of parallel convolutions each extending completely around a portion of said base and each having its sections on opposite sides of said base in the same vertical plane, said base having 120 portions of different lengths for receiving adjacent convolutions of said resistance ribbon and having portions for maintaining adjacent convolutions of said ribbon in a 125 spaced relation.

4. In an electric resistance unit, a stepped insulating base having projections formed thereon, and a single uniform strip of slotted resistance ribbon wound upon said base so that the turns of the same on one side of said base lie directly opposite the turns on the opposite side and in a parallel plane.
5. In an electric resistance unit, a stepped base, strips of slotted ribbon resistance material positioned on said steps and insulated from each other, and means connecting the ends of said strips for permitting the strips on one side of said base to occupy positions directly opposite the strips on the other side.
6. An electric resistance unit having an insulating base, a continuous uniform strip of slotted resistance ribbon wound on said base with its turns spaced apart, the convolutions of the ribbon formed by the slots being so bent at the end of each turn of the ribbon that the turns may be connected together by a convolution of the ribbon

with the sides of each turn opposite and parallel to each other.

7. An electric resistance unit having an insulating base, a continuous uniform strip of slotted resistance ribbon wound on said base with its turns spaced apart, said ribbon being bent back on itself at the end of each turn and folded over laterally whereby one of the convolutions formed by the slots is bent back on itself, said convolution being reversely bent back on itself at its other end whereby the turns are connected together by said convolution so that they may be wound on the base with the sides of each turn directly opposite and parallel to each other.

In witness whereof, I have hereunto subscribed my name in the presence of two witnesses.

HARRY W. DENHARD.
